UNITED STATES PATENT OFFICE.

EDGAR H. FREEMAN, OF TRENTON, NEW JERSEY.

CAP AND SHELL FASTENING FOR LAMP-SOCKET CASINGS.

1,090,527.

Specification of Letters Patent. Patented Mar. 17, 1914.

Application filed April 11, 1912. Serial No. 689,967.

To all whom it may concern:

Be it known that I, EDGAR H. FREEMAN, a citizen of the United States, residing at Trenton, in the county of Mercer and State 5 of New Jersey, have invented certain new and useful Improvements in Cap and Shell Fastenings for Lamp-Socket Casings, of which the following is a specification.

This invention relates to the subject of 10 metallic casings for electrical lamp sockets, and more particularly to casings of the adjustable type wherein a plurality of locking positions are provided between the shell and cap parts of the casing so as to enable the 15 casing shell to not only be readily and securely united to the cap after the latter has been fitted in place, but also to permit the shell to be so positioned when locked to the cap as to present the switch-key (of a key 20 socket) in a readily accessible and convenient position for manipulation.

To this end the present invention contemplates a simple and reliable fastening connection between the shell and cap parts of 25 the lamp socket casing, which admits of practically a universal circular adjustment for the shell so that the same may be locked by the same locking means in any of a number of different positions, while at the same 30 time preserving all of the desirable features of that type of lamp socket casing having what is termed in the trade a "snap fastening."

A further object of the invention is to 35 provide an improved fastening connection between the shell and the cap parts of a casing which dispenses with the necessity of a locking hole or its equivalent to secure the locked parts against rotation in either 40 direction, and against separation, thus greatly simplifying a fastening of this character while at the same time retaining the maximum strength of the casing.

With these and other objects in view, the 45 invention consists in certain novel combinations and arrangements of the parts as will more fully appear as the description proceeds, the novel features thereof being pointed out in the appended claim.

50 For a full understanding of the invention, reference is to be had to the following description and accompanying drawings, in which:—

Figure 1 is a perspective view of a lamp 55 socket casing constructed in accordance with the invention, the cap being shown as sepa-

rated from and elevated above the body portion of the casing. Fig. 2 is a vertical sectional view through the lamp socket casing, the body portion being shown as separated 60 from the cap and properly positioned with respect thereto to be forced into the cap and brought into an interlocking connection therewith. Fig. 3 is a similar view showing the position assumed by the parts after the 65 upper end of the body portion has been forced into the cap, before the body portion has been rotated to bring the lugs of the cap into the lateral arms of the bayonet slots of the body portion. Fig. 4 is a similar view 70 showing the position assumed by the parts after the body portion has been pushed into the cap and rotated to produce an interlocking connection between the members, and Fig. 5 is a transverse sectional view on the 75 line 5—5 of Fig. 4.

Corresponding and like parts are referred to in the following description and indicated in all the views of the drawings by the same reference characters.

The improved fastening forming the subject-matter of this application may be employed in connection with any approved type of two part casing for electrical lamp 80 sockets, although for illustrative purposes the invention is shown in the drawings as embodied in a metallic lamp socket casing comprising a metallic shell or body part 1 and a cap part 2, the said cap part being provided with a peripheral flange 3 which 85 telescopically receives an end portion of the shell or body portion 1.

The end of the shell 1 which is telescopically engaged by the flanged portion of the cap 2 is formed with a series of equidistant or regularly spaced bayonet positioning slots 4 which open through the end of the shell. The end of the shell may also be formed with a suitable slot or opening 5 to receive the switch key, although this slot 90 may be omitted where the key is not used. The flanged portion of the cap 2 is formed with a series of equidistant lugs 6 which correspond in number and position to the bayonet positioning slots 4 of the shell 1. It will 95 thus be obvious that by inserting the end of the shell or body portion 1 into the cap 2 in such a manner that the lugs 6 will enter the bayonet slots 4, and then rotating the shell or cap to bring the lugs into the lateral arms of the bayonet slots an interlocking 100 connection will be produced which will hold 105

110

the shell and cap together and prevent the said members from being separated by a direct pull.

The mouth of one of the bayonet positioning slots 4 is normally closed by means of a resilient locking tongue 7, the free end of the said locking tongue being substantially flush with the edge of the casing and being bent inwardly to provide a guide lip 8 for engagement with the end of that one of the lugs 6 which enters the bayonet slot. When the shell is forced into the cap 2, the end of one of the lugs 6 will ride downwardly upon the inwardly bent guide lip 8 and thereby force the resilient locking tongue 7 inwardly, the parts assuming the position shown in Fig. 3. Upon rotating either the shell 1 or the cap 2 to bring the lugs 6 into the lateral arms of the bayonet slots, as indicated in Fig. 4, the resilient locking tongue 7 will spring back into position so as to fit against one side of the lug and coöperate therewith to prevent backward rotation of the shell. The mouth of the bayonet slot is then effectively closed by the resilient locking tongue, so that the shell and cap can not be accidentally detached from each other.

The resilient locking tongue 7 is shown as constituted by one end of a strip of spring metal which is applied to the interior of the shell 1 and has the lower or inner end thereof connected to the shell in any suitable manner, such as by means of the rivet 9. An intermediate portion of the spring strip is formed with a plunger 10 which passes loosely through an opening in the side of the shell. When it is desired to disconnect the shell and cap, it is merely necessary to press inwardly upon the plunger 10 and throw the

resilient locking tongue 7 into an inoperative position, preparatory to manipulating the shell or cap to release the lugs 6 from the bayonet slots 4.

Attention may be directed to the fact that with the bayonet positioning slots 4 and the lugs 6 arranged at uniform intervals, the casing may be interlocked with the cap with the key receiving slot 5 on any side thereof, the fineness of the adjustment which is possible depending upon the number of bayonet slots and lugs which are employed. It will be obvious that any desired number of the bayonet positioning slots may be utilized, although for ordinary purposes it has been found that four of these positioning slots answer all practical requirements.

Having thus described the invention, what I claim as new and desire to secure by Letters Patent, is:—

A cap and shell fastening for lamp socket casings comprising, in combination, a cap member provided with a plurality of equidistant lugs, a shell member provided with a plurality of equidistant bayonet slots corresponding in number and spacing to said lugs, and a resilient locking tongue permanently fitted to one of said members and having an exteriorly exposed operating means, the said locking tongue being normally sprung into the mouth of one of the bayonet slots substantially flush with the edges thereof.

In testimony whereof I hereunto affix my signature in the presence of two witnesses.

EDGAR H. FREEMAN.
